(57) **CLAIM**

The ornamental design of a connector, as shown and described.

DESCRIPTION

FIG. 1 is a right side elevation view of a connector showing my new design;

FIG. 2 is a bottom plan view thereof;

FIG. 3 is a left side elevation view thereof;

FIG. 4 is a top plan view thereof;

FIG. 5 is a front elevation view thereof;

FIG. 6 is a rear elevation view thereof; and,

FIG. 7 is a perspective view thereof.

The broken line showing of unclaimed internal detail in FIGS. 5 and 6 is included for illustrative purposes only and forms no part of the claimed design.
